UNITED STATES PATENT OFFICE

WILLIAM T. SAVAGE, OF PHILADELPHIA, PENNSYLVANIA, ASSIGNOR TO PHILADELPHIA METAL DRYING FORM COMPANY, OF PHILADELPHIA, PENNSYLVANIA, A CORPORATION OF DELAWARE

DRYING APPARATUS

Application filed March 8, 1928. Serial No. 260,151.

This invention relates to apparatus for drying textile manufactures, particularly knitted wares such as hosiery. More specifically speaking my invention is concerned with 5 drying apparatus of the type employing hollow drying forms through which a fluent heating medium is circulated. With use of such apparatus heretofore, considerable difficulty has been experienced in maintaining 10 the forms uniformly heated due to trapping of air—e. g. in the toe pockets of hosiery forms—with attendant checking of the flow of the fluent heating medium at the designated regions and consequent uneven drying 15 of the stockings. The foregoing is especially true in instances where attempts have been made to employ hot water as the heating medium.

The object of my invention is to overcome 20 the drawbacks pointed out, and this desideratum I aim to attain through provision of simple and reliable means capable of continuously and automatically relieving and carrying off trapped air without loss of heat- 25 ing medium from the apparatus.

A further aim of my invention is to enable 30 in connection with drying apparatus of the character referred to, use either of steam or hot water as heating agents.

Still further objects and attendant advantages will become apparent from the detailed 35 description which follows when taken in connection with the drawing which shows more or less diagrammatically, a drying apparatus 45 conveniently embodying my invention, certain portions being broken away and in section to better illustrate underlying details.

As herein delineated, the apparatus comprises a multiplicity of vertically-arranged 50 drying forms 5—in the present instance for hosiery—disposed in serial relation and secured to a common horizontal manifold 6 which is supported at an elevation above the floor, with a slight slope for drainage toward its right hand end, by suitable transverse standards 7. The forms 5 are of hollow configuration and internally sub-divided by a medial longitudinal partition 8 into up and down flow passages 9, 10 for a fluent heating medium in the direction indicated by the ar-

rows. The manifold 6 serves to receive the flow of the heating medium after it has coursed through the forms 5 via ports 11 communicating with the passages 10 of the latter. The supply flow of the heating medium is 55 conducted through a manifold pipe 12 that extends longitudinally through the manifold 6, said manifold pipe having nipples 13 extending up into the passages 9 of the individual forms. At its inner end, the flow pipe 60 12 is closed by a cap 15, while at its outer end it is connected to mains 17, 18 leading from sources of steam respectively at high and low pressures, which, in practice, may be in the neighborhoods of 5 to 20 and 0 to 5 65 pounds, suitable control valves 19, 20 being interposed in the piping for selectivity as between the two pressures in accordance with the material embodied in the stockings being dried. Also connecting into the manifold 70 pipe 12 is a stand pipe 21 that extends downward from an overhead expansion tank 22. A water feed pipe 23 communicating with a suitable source of supply (not shown), enters the side of the tank 22 near the top. 75 Water flow into the tank is automatically controlled by a float 25 governing a valve 26 fitted to the terminal end of the pipe 23 within said tank. Provisions are also made to take care of overflow, in the form of a pipe 80 27 leading from the side of the tank 22 above the water feed pipe 23. A hand valve 28 near the lower end of the stand pipe 21 serves as a means to shut off the water from the manifold pipe 12 when steam is used as the heating 85 medium.

At its rear end, the inflow manifold 6 is provided with a drop fitting 30 which terminates in a sediment trap 31 at a level below the connection with a return pipe 32. Interposed in a branch 33 of the return pipe 32 is a motor driven pump 34 which delivers into a horizontal conduit 35. This conduit 35 leads to the coil 36 of a water heater 37; and said coil is in turn connected at its top to the 90 manifold pipe 12 through a branch 38. Any suitable medium may be employed to heat the water; but for convenience I prefer to use steam which is delivered through a connection 39 from the high pressure steam main 95 100

17 under control of a valve 40. An extension 41 of the return line 32 terminating in a steam trap 42, has a hand valve 43 interposed in it at a point slightly in advance of a bottom 5 drain connection 44 from the jacket of the heater 37, said connection 44 being fitted with a check valve 45 permitting downward flow only. After being freed of impurities in the trap 42, the steam is conducted back 10 to the source from whence it originally came by a pipe 46.

As a means to automatically control the temperature of the water when the latter is employed as a heating medium, I equip the 15 apparatus with a thermostatic device which may be of any standard construction, the same being conventionally represented at 47 and shown as lying within the conduit 35 previously mentioned. This thermostatic device 47 governs, through a tubular connection 47a, a steam flow regulating valve 48 in the pipe branch 39 which leads to the water heater 37.

To prevent the apparatus from becoming 20 air bound either under steam or hot water operation, I provide means as follows:—Extending vertically of the interior of each of the drying forms 5 is a small caliber tube 50 with its top end open at the highest point 25 within the form—in the present case at the tip of the toe where air is likely to be trapped and prevent circulation of the fluent heating medium around the top of the partition 8. As shown, the several tubes 50 extend downward 30 through the manifold 6 to a common main 51 underlying said manifold. The main 51 slopes downward slightly toward the left in the illustration, and has a vertical drain branch 52 with a hand valve 53 that is normally 35 kept closed. From the right hand or highest end of the main 51 leads an air and vapor relief tube 55, the same entering the stand pipe 21 near the lower end and extending upward axially within it as at 55a. For 40 a purpose later on explained, the horizontal portion of the relief tube 55 is somewhat inclined upwardly toward the left in the illustration, and its terminal end 55b is open at a level above the water in the expansion tank 45 52. For drainage of the apparatus in its entirety, I have shown a cross connection 56 with a valve 57 between the pipe 41 and the downward branch 52 of the main 51.

With use of water as the heating medium, 55 the operation of the apparatus is as follows:—As a pre-requisite, the valves 19 and 20 in the steam mains 17, 18 are of course closed; and the valve 28 in the stand pipe 21 and the valves 53 and 57 controlling flow into the drain 52 opened. Water is thereby permitted to flow into the manifold pipe 12 from the tank 22, the supply in the latter being constantly replenished the while 60 through automatic action of the float valve 26. With assurance that the system is filled

70 with water (determinable through discharge of water through the drain 52), the valves 53 and 57 are shut-off, thereby establishing a closed circulatory system which includes the manifold pipe 12, the forms 5, the manifold 6, the return pipe 32, the pump 34, the conduit 35 and the water heater 37. The valve 40 is thereupon opened to admit steam to the jacket of the water heater 37, and the pump 34 set in motion to induce circulation 75 of the water through the system as indicated by the full line arrows in the illustration. When once heated, the water is maintained at the proper temperature through automatic regulation of steam flow to the heater 37 by the valve 48 under control of the thermostatic device 47 which may be set to function at the desired degree with aid of a thermometer, such as shown at 58 in the conduit 35, as a 80 guide. The air released incidentally to the heating of the water will naturally find its way to the toe tips of the forms 5 wherefrom it is forced, under pressure of the circulating water, into the ends of the release tubes 50 within said forms. The air, as well as water 85 carried along with it in the tubes 50, is conducted to the main 51, and from thence, via the relief tube 55, into the expansion tank 22 above the level of the water in the latter. In this way it will be seen that the relief of 90 trapped air is effected automatically without loss of water from the system. Evaporation taking place over long periods of operation with water is compensated for by automatic action of the float controlled valve 95 26 in the water feed main 23 which permits flow of additional water into the expansion tank 22 as needed from time to time.

The operation of the apparatus with steam 100 is more or less identical as regards circulation through the manifolds 6, 12, the forms 5, and the return piping 32. However, to prepare the apparatus for steam operation the procedure is as follows:—the valve 28 in the stand pipe 21 is first shut off, and the 105 valves 53 and 57 opened to permit drainage of the water remaining in the system through the pipe 52. With this accomplished, the pump 34 is stopped and the valves 53, 57 are closed, and then either the valve 19 or the 110 valve 20 opened for supply of steam from the mains 17, 18—depending on the pressure desired or required for a particular grade or 115 quality of goods to be dried. The course of the steam through the apparatus beyond the 120 return pipe 32 is in accordance with the dotted line arrows in the drawing. Relief of air under steam operation takes place, as before, through the tubes 50 into the main 51 and from thence to the water tank 22, the vapor 125 carried along with the air being therefore also released in said tank and its condensation conserved for re-use in the system. In this connection it will be noted that any water precipitated in the relief tube is obliged, 130

by virtue of the slope of the latter, to flow rearward into drain line 51. The tube 55 is thus kept open at all times for free passage of the air and vapor. When the pipe 51 does become filled with water as will occur from time to time, it may be readily drained by opening the valve 53 for a few moments.

Having thus described my invention, I claim:

1. Drying apparatus of the character described comprising a multiplicity of hollow dryers with coordinating flow and return piping to constitute a closed circulating system for a fluent heating medium, and means for continuously and automatically conducting away trapped air from the highest point within the dryers without wastage from the system of any heating medium carried along with such air.

2. Drying apparatus of the character described comprising a multiplicity of hollow dryers with coordinating common flow and return piping constituting a closed circulatory system, connections permitting selective use either of steam or hot water as the heating medium in the system, and means for continuously and automatically conducting away trapped air from the highest point within the dryers without wastage from the system of heating medium carried along with such air.

3. Drying apparatus of the character described comprising a multiplicity of hollow dryers with coordinated flow and return piping constituting a closed circulatory system, connections permitting selective use either of steam or hot water as the heating medium in the system, a stand pipe topped by an expansion tank connecting into the piping aforesaid, and means for continuously and automatically conducting trapped air and any heating medium carried along with it, from the highest point within the dryers for release at a point above the water level in the expansion tank and conservation of the heating medium for re-use.

4. Drying apparatus of the character described comprising a multiplicity of hollow dryers with coordinated flow and return piping to constitute a closed system for circulation of water through the forms, and means to continuously conduct away trapped air from the highest point within the dryers and discharging it within the system so as to retain within the system any water carried along with such air.

5. Drying apparatus of the character described comprising a multiplicity of hollow dryers with coordinated common flow and return piping to constitute a closed circulatory system for hot water, a stand pipe with an expansion tank at the top connecting into said piping; and air relief means including open-ended tubes leading from the highest

point within the individual dryers, a common main into which the tubes discharge, and a tube extending from said main and delivering at a point above the water level in the expansion tank aforesaid with conservation in the system of any water carried along with the trapped air.

6. Drying apparatus of the character described comprising a multiplicity of hollow dryers with coordinating flow and return piping to constitute a closed circulating system for a fluent heating medium, and means for continuously and automatically conducting away trapped air from within the dryers, said means comprising tubes extending within the dryer and having an air-receiving end opening into substantially the highest point within the respective dryers and an air-discharging end within the system and from which any heating medium carried along with the air is discharged into the system.

7. Drying apparatus of the character described comprising a multiplicity of hollow dryers with coordinating flow and return piping to constitute a closed system for a fluent heating medium, a water reservoir and connections therefrom to the circulating system, and means for conducting away trapped air from the highest point within the respective dryers; said means comprising tubes opening into substantially the highest points within the respective dryers and a conduit connected with said tubes and opening above the water level of the water reservoir.

8. Drying apparatus of the character described comprising a multiplicity of hollow dryers with coordinating flow and return piping to constitute a closed system for a fluent heating medium, a water reservoir and connections therefrom to the circulating system, and means for conducting away trapped air from the highest point within the respective dryers; said means comprising tubes opening into substantially the highest points within the respective dryers, a drain line with which said tubes connect for carrying off liquid and a conduit connected with said drain pipe for carrying off air and vapor.

9. Drying apparatus of the character described comprising a hollow dryer having a closed end and provided with a partition extending toward said closed end, and coordinated flow and return piping constituting a closed system for circulation of a fluid heating medium, and a tube extending within the dryer and beyond the partition and having an air-receiving end opening into the dryer at a point substantially closer than the end of the partition to the closed end of the dryer.

10. Drying apparatus of the character described comprising a multiplicity of hollow dryers with coordinating flow of return piping to constitute a closed circulating system for a fluent heating medium, an inclined drain

pipe extending beneath the dryers, tubes extending within the dryers and having air-receiving ends opening into substantially the highest points within the dryers and communicating with said drain pipe, and a vapor relief tube extending upward from said drain pipe.

In testimony whereof, I have hereunto signed my name at Philadelphia, Pennsylvania, this 3rd day of March, 1928.
